UNITED STATES PATENT OFFICE.

FRANKLIN WOOD HAGAR, OF NASHVILLE, TENNESSEE.

CARBURETER FOR HYDROCARBON-ENGINES.

No. 802,038.

Specification of Letters Patent.

Patented Oct. 17, 1905.

Application filed April 19, 1904. Serial No. 203,863.

To all whom it may concern:

Be it known that I, FRANKLIN WOOD HAGAR, a citizen of the United States, and a resident of Nashville, in the county of Davidson and 5 State of Tennessee, have invented certain new and useful Improvements in Carbureters for Hydrocarbon-Engines, of which the following is a specification.

My invention relates to carbureters for explosive-engines of that type in which the amount of air admitted to the mixing-chamber of the carbureter and fed therefrom to the engine-cylinder is automatically proportioned in relation to the suction created in the mixing-chamber and in which the hydrocarbon is fed to the mixing-chamber by means of the suction created in the latter and the quantity fed is automatically proportioned in reference to the suction created or in proportion to the 20 amount of air admitted to the mixing-chamber.

One of the primary objects of this invention is to provide a carbureter of this type which is particularly simple in construction and highly efficient in operation and in which 25 means are provided for varying the effective action of the suction, created in the mixing-chamber, upon the feed of hydrocarbon, without resorting to means for throttling the feed-passage for the latter.

30 Other objects of the invention will appear and the advantages of the same be appreciated as the construction is more fully disclosed.

To obtain the ends sought, the invention includes the combination and arrangement of 35 component parts to be hereinafter described, and particularly pointed out in the claims.

Although the invention is susceptible of various modifications, the accompanying drawings illustrate and the following specification 40 will describe in connection therewith what is now conceived to be a preferred form of the same.

In the drawings, Figure 1 is a vertical transverse sectional view of the carbureter. Fig. 45 2 is a detail sectional view on the line 2 2, Fig. 1; and Fig. 3 is a detail sectional view on the line 3 3, Fig. 1.

The invention includes generally a suction-chamber, a maintained level hydrocarbon-supply, an unobstructed duct, leading from the latter to the suction-chamber, in which the hydrocarbon is maintained at substantially a constant level, a mixing-chamber, in communication with the suction-chamber, designed 55 to communicate with the engine-cylinder and having an air-inlet opening, means for vary-

ing the effective area of the latter controlled by the suction created in the mixing-chamber, and means for varying the degree of suction created in the mixing-chamber and there-through the amount of hydrocarbon fed to the mixing-chamber in reference to the quantity of air admitted to the latter. 60

In the illustrated exemplification of my invention a reservoir for the hydrocarbon is indicated by 1, from which leads a duct 2, having a vertically-arranged portion 3, in which the hydrocarbon is maintained at a substantially constant level by a float-controlled valve 4, located in the reservoir 1, which controls a 65 supply-passage 5, leading to the latter. A suction-chamber 6 is arranged in communication with the upper end of the duct 3, which chamber is provided with an air-inlet passage 7, the effective area of which is controlled by 70 a valve 8. Preferably surrounding the suction-chamber 6 is a mixing-chamber 10, which is in communication at its upper portion with an exit-opening 15, is in communication at its lower end with an air-inlet opening 11, and is 75 in open communication with the suction-chamber 6 through the intermediary of ports 9. A valve 12 is provided for controlling the effective area of the opening 11, and associated therewith is a spring 13, which tends to normally hold the valve to its seat against the 80 lifting force of the suction created in the mixing-chamber. 85

In the particular embodiment of my invention disclosed in the accompanying drawings 90 a main shell is provided which forms the reservoir-chamber 1 and a second chamber 1^a, within which the mixing and suction chambers are located and which is provided with an internally-threaded portion 14 at its upper 95 open end, with the discharge-opening 15, and with an inlet-chamber 16 at its bottom, with which a series of ports 17 are in communication and from which the opening 11 leads. A cap 18 is threaded in the upper end of the 100 chamber 1^a and is provided with a depending open-ended barrel 19 of slightly less diameter than said open chamber, having an external flange 20, that bridges the space between the periphery of the barrel and the internal 105 wall of the second chamber below the opening 15 and provides, with said periphery, internal wall, and under surface of the cap to the outside of the barrel, a chamber 21, into which the opening 15 directly leads. A plurality of orifices 19' are provided in the wall 110 of the barrel 19, through which the explosive

mixture formed in the chamber 10 passes into the chamber 21 on its way to the engine-cylinder, and these orifices act to insure a thorough intermixture of the hydrocarbon and air by breaking up any imperfectly-mixed strata which may exist and which otherwise might pass through the opening 15 and therefrom to the engine-cylinder. The cap 18 is provided with an axial opening, with a chamber 22, surrounding the latter, and with radial openings 23, leading through its wall. A sleeve 24 is arranged in the axial opening of the cap, extends below the latter through the barrel 19 axially thereof, and at its lower end is continued in a nozzle 25, which is held at its lower end in the bottom wall of the chamber 1^a and is provided at its upper end with a flange 26, preferably integral with a corresponding flange on the lower end of the sleeve. The ports 9 preferably extend radially through the flange 26, and the vertically-extending duct 3 is preferably disposed axially of the nozzle. The mixing-chamber 10 is formed between the external wall of the sleeve and the internal wall of the barrel and is contracted near its lower end by the flange 26. The valve 12 for controlling the air-admission opening 11 is preferably guided upon the nozzle 25, and the spring 13, which tends to hold it upon its seat, is coiled about the nozzle 25 and is interposed between the rear face of said valve and the flange 26. As will be noted, the ports 9 discharge transversely or radially of the mixing-chamber at the lower contracted end thereof, and as the air admitted through the opening 11 must pass through this contracted portion in order to enter the major portion of the mixing-chamber this construction insures the air being thoroughly impregnated with the hydrocarbon. The sleeve 24 is provided with one or more ports 27, which lead through its wall, near the upper end thereof, and place the interior of the same in communication with the chamber 22 and at its lower end with a conical valve-seat 28, which is arranged at the upper end of the opening 7, which leads into the suction-chamber 6 from the interior of said sleeve. The valve 8 has an enlarged stem portion threaded in the upper part of the sleeve 24, an operating-handle to the outside of the sleeve, a contracted stem portion depending through the sleeve, and a conical end coacting with the seat 28. Between the contracted portion of the stem and the internal wall of the sleeve a passage-way is provided which communicates with the outside of the carbureter through the openings or passage-ways 22, 23, and 27, the areas of which are sufficient to admit enough air into the suction-chamber 6 when the valve 8 is open to a maximum extent to prevent a sufficient degree of vacuum being created in said suction-chamber to feed the hydrocarbon from the duct 3.

In the operation of my carbureter the valve 12 is lifted from its seat by the suction cre-

ated in the chamber 10, which permits air to flow in through the opening 11, and the suction created in the chamber 6 at the same time lifts a supply of hydrocarbon from the duct 3 and feeds the same through the ports 9, where it is picked up by the air flowing through the contracted portion of the chamber 10 and carried upwardly in said chamber and thoroughly intermixed therein. The mixture from the chamber flows through the orifices 19' into the chamber 21 and therefrom through the opening 15 to the engine. As will be understood, the amount of air admitted through the opening 11 will depend upon the degree of suction created in the mixing-chamber, and the amount of hydrocarbon fed through the ports 9 will also depend upon the strength of this suction. By means of the valve 8 the completeness or degree of vacuum which it is possible to obtain in chamber 6 may be varied and therethrough the amount of hydrocarbon which will be fed for a predetermined degree of suction in the mixing-chamber can be varied without throttling the feed-duct for the hydrocarbon, and when the parts have been set to feed a certain proportion of hydrocarbon to a given body of air drawn in through the opening 11 this relation will be maintained under variations in the degree of suction created in the mixing-chamber, or the proportions of hydrocarbon and air fed to the mixing-chamber will be substantially maintained under variations of the amount of air drawn into the latter.

The construction and operation of my invention will be readily understood upon reference to the foregoing description and accompanying drawings, and it will be appreciated that the parts and combinations recited may be varied within a wide range without departing from the spirit and scope thereof.

Having thus described my invention, what is claimed as new, and desired to be secured by Letters Patent, is—

1. In a carbureter, a mixing-chamber having an open end, a main air-inlet port, means for controlling the latter, a suction-chamber arranged within the end of the mixing-chamber, contracting the area of the latter, and having ports discharging transversely of the contracted portion thereof, a sleeve disposed axially of the mixing-chamber with its bore communicating at one end with the suction-chamber and at its opposite end with the exterior of the carbureter, a valve for controlling the communication between said bore and the suction-chamber, and a feed-duct in communication with the suction-chamber, substantially as described.

2. In a carbureter, a nozzle having a feed-duct leading therethrough, an air-inlet passage arranged in axial alinement with the feed-duct, a suction-chamber interposed between the duct and passage-way having an opening communicating with the latter, a valve for controlling

the effective area of said opening, a main air-inlet passage, a mixing-chamber in communication with the engine-cylinder and with the main air-inlet opening through a passage-way 5 surrounding the suction-chamber, and ports leading from the suction-chamber into the latter passage-way, substantially as described.

3. In a carbureter, a nozzle having a feed-duct leading therethrough, an air-inlet passage 10 arranged in axial alinement with the feed-duct, a suction-chamber interposed between the duct and passage-way having an opening communicating with the latter, a valve for controlling the effective area of said opening, a main air-inlet passage, a mixing-chamber in communication with the engine-cylinder and with the main air-inlet opening through a passage-way 15 surrounding the suction-chamber, and ports leading from the suction-chamber into the latter passage-way, said ports discharging transversely of said passage-way, substantially as described.

4. In a carbureter, a vertically-arranged chamber, a nozzle extending upwardly there- 20 in having a feed-duct, means for maintaining a substantially constant level of hydrocarbon in the duct, a cap closing the upper end of the chamber having a barrel depending from the same constituting one wall of a mixing- 25 chamber, a sleeve extending through the cap and axially of the barrel constituting the opposite wall of the mixing-chamber and coacting with the upper end of the nozzle to provide a suction-chamber with which the interior 30 of the barrel communicates and which is in open communication with the feed-duct, said cap and sleeve having communicating passages through the same leading from the interior of the sleeve to the exterior of the 35 cap, ports leading from the suction-chamber to the mixing-chamber, a valve adjustably mounted in the sleeve for varying the effective area of the communicating passage-way between the interior of the sleeve and the suc- 40 tion-chamber, said mixing-chamber having an air-inlet opening, and a valve for controlling the latter actuated by the suction created in the mixing-chamber, substantially as described.

5. In a carbureter, a main shell including a reservoir-chamber and a second chamber having an open upper end, an opening leading through the side wall of the second chamber providing an exit therefrom, and a second 45 opening in the lower portion of the second chamber providing an inlet, a cap fitted to the upper end of the second chamber having a depending barrel provided with orifices, a sleeve fitted to the cap and depending there- 50 from through the barrel and providing with the latter and the cap a mixing-chamber, a nozzle arranged axially of the second chamber below the sleeve and providing therewith a suction-chamber from which ports lead to 55 the mixing-chamber, said nozzle having a duct

therein in open communication with the reservoir and said sleeve having a passage-way providing an open communication between the bore of the same and the suction-chamber, and other passage-ways coacting with the 60 passage-ways in the cap to provide open communication between said bore and the exterior of the cap, a valve adjustably mounted in the sleeve having a portion for varying the effective area of the passage-way leading to the 65 suction-chamber, and a part extending without the cap for manipulating the valve, and a spring-pressed valve for controlling the effective area of the inlet-opening in the second chamber, substantially as described. 70 80

6. In a carbureter, a main shell including a reservoir-chamber and a second chamber having an open upper end, an opening leading through the side wall of the second chamber providing an exit therefrom, and a second 75 opening in the lower portion of the second chamber providing an inlet, a cap fitted to the upper end of the second chamber and having an open-ended barrel depending therefrom, of less diameter than the second chamber, and provided with orifices leading through its wall and with a peripheral flange at its lower end contacting with the wall of the second chamber to provide a chamber with which the exit-opening and orifices communicate, a 80 sleeve arranged axially of the plug, depending therefrom and terminating in a nozzle having a feed-duct, said sleeve providing with the barrel a mixing-chamber and with the nozzle a suction-chamber, a flange at the meeting ends of the nozzle and sleeve having ports leading through the same for placing the mixing-chamber and suction-chamber in communication, and said flange contracting the lower 85 portion of the mixing-chamber to provide a 90 reduced passage-way for the air admitted thereto from the inlet-opening, air-passages leading from the outside of the carbureter to the bore of the sleeve, a passage-way between said bore and the suction-chamber having a 95 valve-seat at its upper end, a valve arranged axially of the sleeve for varying the effective area of said passage-way, a valve guided on the nozzle and controlling the inlet-opening, and a spring interposed between said valve 100 and said flange, substantially as described. 105

7. In a carbureter, a main shell including a reservoir-chamber and a second chamber having an open upper end, an opening leading through the side wall of the second chamber providing an exit therefrom, and a second 110 opening in the lower portion of the second chamber providing an inlet, a cap fitted to the upper end of the second chamber and having an open-ended barrel depending therefrom of less diameter than the second chamber, provided with orifices leading through its wall and with a peripheral flange at its lower end contacting with the wall of the second chamber to provide a chamber with which the exit- 115 120 125 130

opening and orifices communicate, a sleeve arranged axially of the plug, depending therefrom and terminating in a nozzle having a feed-duct, said sleeve providing with the bar-
5 rel a mixing-chamber and with the nozzle a suction-chamber, a flange at the meeting ends of the nozzle and sleeve having ports leading through the same for placing the mixing-chamber and suction-chamber in communication, and said flange contracting the lower portion of the mixing-chamber to provide a reduced passage-way for the air admitted thereto from the inlet-opening, air-passages leading from the outside of the carbureter to
10 the bore of the sleeve, a passage-way between said bore and the suction-chamber having a
15

valve-seat, a valve arranged axially of the sleeve coating with the seat for varying the effective area of said passage-way, and a valve associated with said inlet-opening and controlled by the suction created in the mixing-chamber, substantially as described. 20

In testimony whereof I have hereunto signed my name, in the presence of two attesting witnesses, at Nashville, in the county of David-
son and State of Tennessee, this 11th day of April, 1904. 25
